WEATHER STRIP MEANS FOR DOUBLE HUNG SASH

Henry Hasenburger, Newark, N. J., and Harvey Wiley Corbett, New York, N. Y., assignors to PHC Housing Corporation, New York, N. Y., a corporation of Ohio

Application April 19, 1941, Serial No. 389,386

3 Claims.

(Cl. 20—69)

This invention relates generally to weather stripping materials and is particularly directed to sheet metal weather strip means for use on windows of the type having two or more sash mounted for movement in a frame. Heretofore, some forms of weather stripping for this type of window included plates or strips which were positioned between the slideable sash and the walls of guideways formed in said frame. These strips were provided with ribs which extended into channels formed in the sash, the object being the provision of tortuous passages which would preclude the entrance of the elements into the building. This type of weather strip is objectionable because the sash must fit rather tightly in the guideway to prevent air flow and upon becoming damp, will swell and bind, sometimes becoming immovable.

One of the objects of the present invention resides in the provision of weather stripping means which will permit the sash to be relatively loosely mounted and yet preclude the entrance of air into the building, there being a yieldable engagement between various parts of the weather stripped window to compensate for any swelling or warping of the wooden sash during periods of inclement weather.

Another object resides in the provision of weather strip means which may be removed and replaced without destruction of the various parts and with a minimum of labor and inconvenience.

A further object rests in the formation of means of the type mentioned which includes a parting strip adapted to be located between the sash guides and provided with flexible walls on which are formed flange means, the sash being equipped with complementary strips having slideable engagement with the parting strip, the sash strips being engaged with both the walls and flanges whereby a double seal will be produced.

Another object rests in the provision of a novel manner by which the sections of the weather strip means are secured to the frame and sash, the parting strip members being loosely disposed in channels in the frame and the sash strips being inserted in saw slots in the sash, a single securing element being employed to lock each sash strip to its respective sash.

Further objects will be apparent from the following description and the accompanying drawing in which the invention has been illustrated in its preferred form.

In the drawing:

Fig. 1 is a horizontal sectional view taken through one side of a window frame provided

with weather strip means formed in accordance with the present invention, the plane of the section being taken through the upper sash;

Fig. 2 is a vertical sectional view taken through the sash shown in Fig. 1, the plane of this section being indicated by the line II—II of Fig. 1;

Fig. 3 is a detail perspective view of the parting strip section of the weather strip means;

Fig. 4 is a similar view of a weather stop strip which is applied to the sash.

Referring more particularly to the drawing and to Figs. 1 and 2, the numeral 1 designates the window frame. This member includes a side rail 2 and inner and outer strips 3. The latter members project slightly beyond the outer face of the rail 2 to provide guide walls 4 at the side edges of the rail. These walls cooperate with the rail to form a longitudinally extending channel in the frame. Intermediate the side edges of the rail, the outer face thereof is formed with a longitudinally extending groove 5 for the reception of a parting strip 6 which forms a part of the weather strip means. The strip 6 is formed from sheet metal and includes a body 7 provided by bending the material to produce an outer wall 8 and a pair of rearwardly directed side walls 9. These walls terminate at their outer edges in laterally directed sections 10 which in turn terminate in flanges 11 directed toward the sash 12 positioned for sliding movement in the channel formed by the walls 4 and the rail 2.

The side walls 9 of the parting strip are of such width that when the sections 10 are in engagement with the bottom wall of the groove 5, the outer portion of the strip will project a considerable distance beyond the side edges of the sash. This arrangement serves to divide the channel into a pair of guideways, each receiving one of the sash. The side walls 9 of the parting strip converge toward the rail 2 and, intermediate of their width, they are provided with longitudinally extending creases to form narrow diverging sections, the purpose of which will be hereinafter set forth.

The flanges 11 diverge slightly as they approach the sash and are spaced from the side walls 9 to provide recesses for weather stop strips 13 carried by the sash. As illustrated in Figs. 1 and 4, the stop strips include flat body portions 14 and laterally directed flange portions 15, the latter forming an obtuse angle with the former. Toward the outer edge of the flange portion, the edge is curled slightly back toward the plane occupied by the body portion. This manner of bending the stop strips provides longitudinally

extending rounded corners for engagement with the parting strips, the stop strips being disposed within the spaces formed between the flanges 11 and the side walls 9 of the parting strips. When so positioned, the rounded corner formed between the sections 14 and 15 of the stop strips engages the diverging section of the side wall 9 and the outer rounded corner engages the inner surface of the complementary flange 11.

To hold these rounded corners in this engagement with the parting strips, the parting strips are secured to the sash by forming longitudinally extending slots in the sash adjacent to their edges. These strips extend into the sash at an angle to the surfaces, the slot in the upper sash being formed in the inner side while the slot in the lower sash is on the outer side. To retain the stop strips in their positions in the sash, the body section of each stop strip has a perforated lug 16 directed laterally from one end. This lug overhangs one end of the sash and a screw 17 or other suitable securing element projects through the perforation in the lug into the material of the sash to retain the stop strip against longitudinal movement relative to the sash.

After the various parts have been assembled into the positions shown in Fig. 1, the stop strips will have a double engagement with the parting strip to effectively prevent the entrance of air into the building between the sash and the frame. If the sash should swell or shrink due to weather conditions, the stop strips may move into and out of the spaces between the side walls and flanges of the parting strip without affecting the ability thereof to move longitudinally of the window frame. By forming the diverging sections in the walls 9, the stop strips will have a greater extent of engagement with the walls when the sash moves laterally into and out of the guide groove. The diverging sections of the walls 9 also serve to hold the outer portions of the stop strips in firm engagement with the inner surfaces of the flanges 11.

Through the provision of the slots in the sash and the single perforated lug on each stop strip, the weather stripping can be installed on the windows with a minimum of time and effort. The parting strip is merely positioned in the groove 5, no securing elements being necessary. As but a single securing element is used for each stop strip and these elements pass through a perforated lug from the top and bottom ends of the sash, the strips may be installed after the window has been assembled and secured in the building wall. If it is desired to remove the stop strips, the single screw 17 can be withdrawn, permitting the strip to be moved longitudinally in the slot in the sash and then withdrawn from the recess in the parting strip.

As shown in Fig. 2, the lower end of the parting strip is oppositely beveled as at 18 from the central portion to permit the lower end of the strip to engage the inclined surface of the window slide 19. By beveling the strip from the central portion, it may be used on either side of the window frame.

While the invention has been illustrated and described in but a single form, it is obvious that minor changes may be made in the various parts and their relation without departing from the spirit and scope of the invention as set forth in the following claims.

What is claimed is:

1. Weather stripping means for windows having a frame and upper and lower sash mounted for movement in spaced parallel guides, parting strip means disposed in said frame between said sash guides and extending the full length thereof, said parting strips having spaced flexible walls which converge outwardly from said sash, intermediate longitudinally extending portions of said walls diverging, flexible flange means connected to the outer edges of said walls, said flanges being directed toward said sash, the opposed surfaces of said sash being provided with angularly disposed longitudinally extending slots, and weather stop strip means disposed in said slots, said strip means being curved at the outer portion to slidably engage both the diverging portions of said parting strip walls and said flanges.

2. In a window of the type having a frame and upper and lower sash movably mounted in spaced parallel guides provided in said frame, a parting strip disposed between said guides, said strip having flexible diverging walls extending away from said sash and terminating in diverging flanges directed toward said sash, and weather stop strip means projecting from the opposed faces of said sash, said strip means projecting into the space between the walls and flanges of said parting strip, and being curved to engage both the walls and the flanges of said parting strip.

3. Weather stripping for slidable window sash, a window frame having guides in which a pair of window sashes are mounted for vertical sliding movement, said frame being formed on each side thereof with a vertical groove located between said sashes, a metallic parting strip adapted to occupy each of said grooves and coextensive in length therewith, said parting strip providing a metal sheet formed to provide a transversely extending outer wall, inwardly directed side walls and outwardly and laterally bent flanges, the latter having bearing engagement with the wall surfaces of said groove, the intermediate portions of the side walls of said strip occupying planes angularly disposed with respect to those of the continuing inner and outer portions of said side walls, and metallic weather strips carried by and extending the full height of each of said sashes, each of said strips projecting in acute angular relationship from the vertical plane of the sash on which it is mounted and having its free outer portion deflected angularly for resilient wiping engagement with both the angular intermediate portions of one of the side walls of said parting strip and the adjacent side surface of one of said parting strip flanges.
